UNITED STATES PATENT OFFICE.

ABRAHAM SLOTOFF, OF BROOKLYN, NEW YORK.

BATHING SUIT.

Application filed August 29, 1927. Serial No. 216,169.

An object of the present invention is to provide an improved bathing garment having a convertible collar designed for ready adjustment to a plurality of attractive and distinctive forms in order that the ornamental effect of the garment may be varied. 5

Other objects will appear hereinafter.

In the drawing:

Fig. 1 is a front view of the garment with 10 the collar adjusted to one of its open forms;

Fig. 2 a front view of the upper portion of the garment with the collar converted to another open form;

Fig. 3 a similar view showing the collar adjusted to a closed form; and

Fig. 4 an outer face view of an end portion of the collar.

The garment comprises a body or waist 1 made of any suitable fabric and formed at its 20 upper end to surround the neck when closed.

The upper, neck-surrounding edge of the garment body is designated 2. Outwardly of said edge the body is formed with narrow shoulder portions 3 and arm holes 4. At the 25 front the body is formed with an opening slit 5 which extends from the neck-surrounding edge 2 downwardly a suitable distance. Secured within the body along one edge of the opening slit is an inner flap 6 which under- 30 laps the opposite edge of the slit and has a row of buttons 7 stitched to it along the slit. These buttons engage in buttonholes 8 formed in the marginal edge of the body overlying the flap 6. The flap and its row of buttons 35 extend upwardly from the lower end of the opening slit and terminate a material distance below the upper end of the slit. Along the opposite side of the slit from the buttons 7 the body has a corresponding row of buttons 40 9 stitched to it for ornamental effect.

The garment structure includes a collar 10 in the form of a substantially straight band or strip of fabric of substantially uniform width and pointed at the ends. Preferably 45 the band is formed of freely flexible knitted fabric. It is stitched along its lower edge to the edge 2 of the garment body and its length is materially greater than that of edge 2, so that it is provided with free front ends 11 50 which extend beyond the edges of the slit 5, and are formed with buttonholes 12 near their pointed extremities. Stitched to the outer face of the collar at opposite sides of the slit 5 are two buttons 13. These buttons are 55 spaced a material distance back from the slit and from the pointed ends of the collar. Two

buttons 14 are secured to the front of the body 1 at opposite sides of the slit, adjacent the arm holes, and spaced downwardly from the neck almost as far as the uppermost buttons 7 and 9. The upper and lower edges of the collar, the edges of the slit 5, and the edges of the arm holes are all braided as indicated at 15. The braiding of the slit 5 merges with the lower edge of the collar along lines 16 which curve outwardly toward the ends of the collar. At the outer face of the collar is a ring 17 which is stitched to the collar at one point as indicated at 18. This point is located substantially in line with the right hand edge of the slit 5 so that the ring is located upon the collar between one of the buttonholes 12 and one of the buttons 13. 60 65 70 75 80 85 90 95

The collar is designed to be worn either open or closed. An open adjustment thereof is shown in Fig. 1. The upper margin of the collar is here folded down at the back, as indicated by the dotted lines, the collar ends 11 are brought straight down, and their buttonholes 12 engaged with the buttons 14 over the breast. The upper portion of the slit 5 then forms a V which merges gracefully with the downwardly extending pointed ends of the collar; and folds 19 are formed in the body 1 to define an inner V which merges with the sides of the collar. Thus a graceful neck opening is defined and this opening is trimmed at the sides by the depending portions of the collar so that the garment at this point presents a very attractive and distinctive appearance. The collar and the body of the garment are preferably formed of fabrics differing in texture and color in order to enhance the trimming effect of the collar. 100

Another adjustment of the opened collar is shown in Fig. 2. Here the free extended ends 11 of the collar are folded back upon the body of the collar and their buttonholes 12 are engaged with the buttons 13. This second adjustment is a variation of the first to change the ornamental effect. In the adjustments shown in Figs. 1 and 2, the ring 17 is concealed by the collar. 105

In Fig. 3 the closed adjustment of the collar is shown. For this adjustment the collar ends 11 are trained through the ring 17, folded back upon the body of the collar and secured by the engagement of the buttons 13 with the buttonholes 12. The collar then encloses the neck and the ends 11 produce the neat, trim and attractive appearance of a "butterfly" bow. 110

The collar design and the fastening elements thus provide simple means to readily vary the ornamental effect of the garment and produce an attractive and distinctive effect 5 in each adjustment. While I have disclosed the preferred form of my invention I do not wish to be limited to this specific disclosure but reserve the right to make such changes as will lie within the scope of the claims. The 10 fastening elements, for example, may be varied and the invention is obviously adaptable to other forms of garments.

I claim:

1. In a garment, a collar comprising a 15 freely flexible band formed with free extended ends; a ring attached to the outer face of the collar at a point spaced a material distance inward from the extremity of one of said extended ends and adapted to have said 20 ends trained through it to fold back against the outer face of the collar; and fastening means to detachably hold the ends in their folded back positions.

2. An article of manufacture comprising a 25 convertible garment including a freely flexible body or waist portion formed with a front opening slit extending downward from the neck; a convertible collar in the form of a freely flexible straight band stitched along 30 its lower edge to the body and formed with free front ends extending a material distance beyond the opening slit, said band being freely foldable both transversely and longitudinally; fastening means carried by the garment body to releasably hold the front slit closed at a point spaced downward a material distance from the upper end thereof; a pair of fastening means secured to the body below the collar, spaced outwardly a material distance at opposite sides of the slit and adapted to detachably engage the extended collar ends and cooperate with said slit-fastening means to hold the collar open with the back portion thereof folded outward and 45 downward along a longitudinal medial line, the ends extending substantially straight downward and parallel to each other and spaced materially outward from the slit opening, and both the collar and body folded outward obliquely to define an inner V along the fold lines converging downward upon the 50 opposite sides of the collar to said slit-fastening means and an outer V defined by the slit edges converging downward from their junctures with the lower edge of the collar to said slit-fastening means; and means carried by the garment to releasably hold the collar in a closed upstanding adjustment with said V's closed.

3. As an article of manufacture, a garment comprising a freely flexible body or waist portion formed with a front opening slit extending downward from the neck; a convertible collar in the form of a freely flexible band 55 stitched along its lower edge to the body and

formed with free front ends normally lying a material distance laterally beyond the longitudinal line of the opening slit and substantially parallel with each other; fastening means carried by the garment body to releasably hold the front slit closed at a point spaced downward a material distance from the upper end thereof, whereby the collar will be normally open with the back portion thereof folded outward and downward along a longitudinal medial line, the free ends thereof extending substantially straight downward and parallel to each other and spaced materially outward from the slit opening, and both of the front portions of the collar and body 80 will be folded outward obliquely to define an inner V along the fold lines converging downward from opposite sides of the collar to said slit-fastening means and an outer V defined by the upper free unfastened portions of the 85 slit edges converging downward from their junctures with the lower edge of the collar to said slit-fastening means; and means carried by the garment to releasably hold the free ends of the collar.

4. An article of manufacture comprising a convertible garment including a freely flexible body or waist portion formed with a front opening slit extending downward from the neck; a convertible collar in the form of a 95 freely flexible straight band stitched along its lower edge to the body and formed with free front ends extending a material distance beyond the opening slit and each provided with a button-hole, said band being freely 100 foldable both transversely and longitudinally; fastening means carried by the garment body to releasably hold the front slit closed at a point spaced downward a material distance from the upper end thereof; a pair of buttons secured to the body below the collar, spaced outwardly a material distance at opposite sides of the slit and adapted to detachably engage the button-holes in the extended collar ends and cooperate with said 110 slit-fastening means to hold the collar open with the back portion thereof folded outward and downward along a longitudinal medial line, the ends extending substantially straight downward and parallel to each other and spaced materially outward from the slit opening, and both the collar and body folded outward obliquely to define an inner V along the fold lines converging downward upon the opposite sides of the collar to said slit-fastening 115 means and an outer V defined by the slit edges converging downward from their junctures with the lower edge of the collar to said slit-fastening means; and means carried by the 120 garment cooperating with said button-holes to releasably hold the collar in a closed upstanding adjustment with said V's closed.

In testimony whereof I hereunto affix my signature.

ABRAHAM SLOTOROFF.
